UNITED STATES PATENT OFFICE.

JOHN HOSKINS, OF CHICAGO, ILLINOIS.

MUFFLE-FURNACE FOR ASSAYING AND ANNEALING.

SPECIFICATION forming part of Letters Patent No. 315,036, dated April 7, 1885.

Application filed June 28, 1884. (No model.)

To all whom it may concern:

Be it known that I, JOHN HOSKINS, a citizen of the United States, residing at Chicago, in the county of Cook and State of Illinois, have invented a certain new and Improved 5 Muffle-Furnace for Assaying and Annealing; and I hereby declare the following to be a full, clear, and exact description of the same.

My invention relates to a furnace to be 10 heated by gaseous fuel or liquid fuel reduced entirely or almost entirely to a gaseous state and introduced into the combustion-chamber, and preferably by means of the hydrocarbon-gas burner shown, described, and claimed in 15 Letters Patent of the United States No. 267,431, granted to me November 14, 1882.

It is the object of my invention to provide 20 a furnace in which complete or almost complete combustion of the fuel employed shall take place within the combustion-chamber, whereby practically only the heated products 25 of combustion and heat shall enter the oven or muffle-chamber and heat uniformly throughout its whole extent the receptacle contained therein for the substances to be acted upon; and it is my object, further, to provide a furnace that may be used to great advantage for 30 purposes of annealing and enameling by jewelers and dentists, and others who practice such arts.

To these ends my invention consists in a furnace having a combustion-chamber in immediate communication with the oven or muffle-chamber, and inclosed excepting as to the 35 opening which leads to it, and as to such communication.

My invention also consists in providing one or more ovens to rest upon the first oven, and having means of communication with the first 40 oven; whereby the heat and products of combustion may be distributed equally about all parts of the several muffles so superimposed in series; and my invention consists, further, in certain details of construction and combinations of parts, all as hereinafter more fully set forth.

In the drawings, Figure 1 is a perspective view of my improved furnace, showing the position of the muffle within the furnace prop- 45 er or muffle-chamber, and the opening in the

upper side of the latter forming the outlet for the products of combustion; Fig. 2, a sectional end elevation showing the communication of the combustion-chamber with the muffle-chamber containing a muffle, and showing the said 55 muffle-chamber communicating with a second muffle-chamber, represented in broken lines above the first, and likewise containing a muffle, also represented in broken lines; and Fig. 3, a side elevation in section, showing partly 60 in broken lines the construction and relative positions of the combustion-chamber and ovens containing muffles.

A is a muffle-furnace composed of fire-clay or other refractory or incombustible material, 65 and formed, for convenience of construction, in two parts, A' and A², which are secured together by means of metal strips t, bent to a trough shape and caused to inclose the corners. A metallic strap, s, is passed horizontally around the upper margin of the part A², to contribute additional firmness to the same, and is riveted at each side of a corner to the material forming the part A², the rivets passing at the same time through the vertical corner-braces t, to secure the latter at their upper ends. A similar strap, s', is caused to surround the lower side of the part A', for the same purpose that the strip s is provided upon the part A². The part A' rests upon 75 legs r, riveted toward their upper ends to both sides of each lower corner of the same, the rivets entering into the substance composing the part A', and passing through the lower portions of the corner-braces t, to fasten the latter 80 at their lower extremities, and through the strip s', to secure it in position.

B is a combustion-chamber formed in the part A', and comprising, preferably, an inwardly-tapering circular opening, which ex- 85 tends to the wall q.

C is a longitudinal slot formed in the upper side of the combustion-chamber to afford communication between the latter and the muffle-chamber D. The opening leading from the 90 combustion to the muffle chamber may be of any desired form other than the slot C, comprising, for example, perforations through the upper wall of the part A', or an opening of greater width than that of the slot C, but of 95 100

equal or approximately equal length, the purpose being to produce contact of the products of combustion from the chamber B with all parts of the muffle in the muffle-chamber simultaneously, while preventing, owing to the substantially complete combustion which takes place within the chamber B, particularly after the latter shall have once become heated, the entrance of flame into the muffle-chamber. 5 This is found best to be effected by the tapering construction of combustion-chamber above referred to.

The muffle-chamber D is an arch-like opening of equal dimensions throughout, formed 15 in the side of the part A² opposite the side containing the opening B, and extending inwardly to the wall q'.

E is an arch-shaped muffle formed of in-combustible material, and of dimensions to 20 permit it to lie within the muffle-chamber D, and provided with supports p, one under each corner. The part A' is provided on its upper side with an opening, C', similar to the opening C, or to either of the modifications of the 25 latter hereinbefore mentioned, to form an outlet for the products of combustion, or to provide communication with another muffle-chamber, D', containing a muffle, E', and having an opening to correspond with the opening C' upon the same.

Any desired number of muffle-chambers communicable with each other, and corresponding with the part A², may be provided to lie one upon the other, when the heat supplied to each from the one combustion-chamber will diminish in degree as it rises, producing a lower temperature in the top chamber than in the one immediately below it, and so on down, owing to which the various muffle-chambers may be used for carrying out 40 different processes, or the different steps of the same process demanding varying degrees of heat.

To operate my device flame is blown into 45 the combustion-chamber B by means of my hydrocarbon apparatus hereinbefore referred to, which is adjusted to varying distances from the mouth of the combustion-chamber, depending upon the size of such apparatus 50 and of the furnace, to permit mixture with the

flame of air, whereby combustion shall take place to a very great extent before the entrance of flame into the combustion-chamber. The tapering form of the combustion-chamber effects equalization of the discharge of the products of combustion through the slot in the top of the chamber B, and thereby causes, as it is found, the maximum of heat to be utilized, and as the products of combustion enter the muffle-chamber and completely surround the muffle therein the latter is heated equally throughout its whole extent. 55

When more than one muffle-chamber is used, the combustion occurring within the combustion-chamber will always, other things being 60 equal, produce the same variation in degree of the heat from one chamber to the other.

My furnace may of course be employed for purposes other than assaying, annealing, enameling, and the like, and it may of course be 65 formed in any size necessary to render it suitable for the purpose for which it is employed.

What I claim as new, and desire to secure by Letters Patent, is—

1. In a furnace for burning gaseous or liquid fuel, the combination of a muffle-chamber, D, having an opening, C', and a combustion-chamber, B, provided with an opening leading into it and with a passage, C, connecting it with the muffle-chamber, and wholly and 70 permanently inclosed elsewhere, substantially as described, and for the purpose set forth.

2. In a furnace, the combination of an inwardly-tapering combustion-chamber, B, oven or muffle-chamber D, having an opening, C', 75 and passage C, connecting the muffle-chamber and combustion-chamber, substantially as described, and for the purpose set forth.

3. In a furnace, the combination, with a combustion-chamber, B, oven or muffle-chamber D, having an opening, C', and passage C, connecting the muffle-chamber and combustion-chamber, of one or more ovens or muffle-chambers, D', each having an opening, C', as 80 and for the purpose set forth.

JOHN HOSKINS.

In presence of—

THOMAS A. BANNING,
W.M. I. BUNKER.
